UNITED STATES PATENT OFFICE.

ARCHIBALD McA. LANG, OF LIVERPOOL, ENGLAND.

SUGAR-CANE AND LIKE MILL RETURNER-BAR.

1,156,012.

Specification of Letters Patent.

Patented Oct. 5, 1915.

Application filed January 16, 1915. Serial No. 2,681.

To all whom it may concern:

Be it known that I, ARCHIBALD McARTHUR LANG, a subject of the King of England, residing at 17 York street, Liverpool, in the county of Lancaster, England, have invented new and useful Improvements in or Connected with Sugar-Cane and like Mill Returner-Bars, of which the following is a specification.

10 This invention has reference to three roller sugar cane and like mills, and especially to the retuner bar, and parts connected with it, lying between the two lower rollers, and serving to lead or direct the cane delivered from the upper and intake lower roller, and delivering it to the nip between the upper and the second and discharge lower roller.

15 This invention will be described with reference to the accompanying drawings which illustrate it.

20 In the drawings Figure 1 is a cross section through a mill provided with the improvements; and Fig. 2 is an end view of the same. Fig. 3 is a longitudinal section 25 showing a modification.

Referring to the drawings, *a* are the main frames or headstocks of the mill; and *b*, *c* and *d*, the three rollers.

25 *e* is the retuner bar supporting beam, and *e*¹ the retuner bar proper, on the upper edge of same; and *f* are the stools formed or connected with the lower portion of the frames or headstocks *a*, and carrying movable supporting bearing parts *g* by which the beam *e* and supporting parts are adjustable at their lower portions.

30 The beam *e*, as is usual in mills of this kind, and the retuner bar *e*¹, extend across the mill from side to side, inside the main frames or headstocks *a*; and, as in some kinds, of known mills, the beams and their supporting means are adjustable, so that the retuner bar *e*¹ can be adjusted bodily in relation to the rollers *c* and *b* at the intake

35 side, and its leading edge brought into position in relation to the surface of the intake lower roller, and also generally adjusted as required. In some cases, in mills as heretofore constructed, this adjustment has been effected by ordinary movable cutters or wedges, through which the adjustment of the retuner bar in a direction at right angles to the axes of the rollers, and in some cases vertically, can be accomplished; while in 45 other cases, it has been effected by screw-bolt gear, or the like; and in some cases

moreover, the retuner bar beam is capable of being rocked about its lower edge, more or less by threaded rods and nuts or the like; and this invention is directed to mills 60 having retuner bars and beams of the latter character.

In the machine shown, the beam *e* has at each end below, a species of gudgeon or cylindrical base *h*, which is preferably fixed to it by a staple-shaped clamp fastening *h*¹; and this gudgeon or bearing piece on each end rests in a corresponding seat on the movable bearing block *g* which rests on the stool *f* below, formed in one with the headstock 70 or frame *a*.

The bearing block *g* is capable of adjustment longitudinally on the stool *f* by means of screw studs *i* passing through upwardly projecting thrust parts or ends *f*¹ of the 75 stools, and screwing through a nut *j* fitting in a recess in the inside edge of the thrust parts *f*¹, so that they cannot turn around; and the blocks *g* are held down in position by vertical stud bolts and nuts *k*, passing 80 through slotted openings in their ends.

As will be seen, the ends of the stools *f* lie within the ends of the headstocks or frames *a*, and the insides of the thrust parts *f*¹ of the stools are comparatively close to 85 the ends of the bearing blocks *g*.

The upper part of the rocking beam *e* is held and adjusted by means of a long bolt *l* at each end, which fits over a pin *m* on the end of the beam *e* at the upper part; and the bolts extend out to the outside of the mill in an upwardly inclined direction, and pass through lugs or bosses *n* on the inside of the plumber block bearing caps *o* of the intake lower roller *c*. By these means, by screwing 95 up a nut on the end of the bolts or rods *l*, the front edge of the retuner bar *e*¹ may be adjusted up to the surface of the intake lower roller, and held there.

In some cases, the beams and retuner bar 100 are made adjustable vertically, as well as horizontally, and longitudinally; and this is effected by making the bearing blocks *g* wedge shaped below, so that when they are moved longitudinally, they may also by virtue of the wedge shape be adjusted vertically. This construction is illustrated in Fig. 3, and in this figure, which illustrates this modification, for this purpose, there are two blocks, the upper block *g* forming the 110 bearing proper, on which rests the trunnions *h* of the beam *e*, having an inclined

2
lower surface; and another block g^1 below, the upper surface of which is inclined, corresponding to the inclined surface of g , and which is also adjustable longitudinally, and 5 in itself rests on the stool f . In this case, the adjusting bolts i pass longitudinally through the blocks g , g^1 ; and the thrust parts f^1 are cast on the inside of the frame 10 of the machine, instead of on the ends of the stools f ; and they are adjusted longitudinally by means of nuts fitting on the ends of the screw bolts i , as will be understood. Thus by these means, by adjusting both blocks g , g^1 longitudinally together, 15 longitudinal adjustment of the bearing blocks and lower part of the beam e is effected; while, to give vertical adjustment alone, only the lower block g^1 is adjusted longitudinally on the stools f . Hence, longitudinal 20 adjustment only is accomplished by moving both blocks g , g^1 longitudinally together, or equally; longitudinal and vertical adjustment is accomplished by moving the upper block g ; and vertical adjustment 25 is effected by moving the lower block g^1 only longitudinally, the other remaining stationary.

As a modification of the above, one bearing block only of wedge shape, equivalent to 30 g above described may be used; and this may rest on loose plates below, between it and the stool f , so that by moving these together along the stool f , longitudinal adjustment of the bearings for the returner bar 35 beam is effected; while the vertical adjustment is effected by forcing in, in any suitable way, the loose plates under the block g . In this case, as in the former, the blocks are held down by stud-bolts and nuts k , and the 40 thrust blocks f^1 are slotted where the upper bolts i pass through them, to allow for vertical movement of the upper block.

What is claimed is:—

1. In sugar cane and like mill, the combination of an adjustable returner bar; longitudinally adjustable bearing parts; stools on which the said bearing parts are supported; trunnion supports on the returner bar beam, supported by the said bearing parts; bolts 50 for adjusting the said bearing parts; and adjustable bolts connected with the upper part of the returner part beam; substantially as described.

2. In a sugar cane and like mill, the combination of an adjustable returner bar; longitudinally adjustable bearing parts; stools on which the said bearing parts are supported; trunnion supports on the returner bar beam, supported by the said bearing 55 parts; bolts for adjusting the said bearing parts; adjustable bolts connected with the

upper part of the return bar beam; and wedge means for adjusting the returner bar vertically, disposed beneath the said former bearing parts; substantially as described. 65

3. In a sugar cane or like mill, the combination of the frames or headstocks; supporting stools formed on the inner side of same; longitudinally adjustable bearing blocks supported on the said stools; fastening 70 bolts; adjusting bolts; upwardly projecting gudgeons on the bearing blocks; returner bar beam resting at each end on the upper side of the said gudgeons; returner bar on the said beam; and adjusting bolts on the 75 inside of the frames, secured at one end to the said returner bar beam, and the other provided with a nut for adjusting same; substantially as described.

4. In a sugar cane mill, the combination 80 with the returner bar, of means which provides a rocking support for the return bar, means for adjusting said means vertically, means for adjusting said supporting means horizontally, and means for rocking the returner bar on its support.

5. In a sugar cane mill, the combination 90 with the return bar of a bearing block adapted to provide a rocking support for the returner bar; a support for supporting the bearing block, means for adjusting the bearing block horizontally and vertically on its support, and means for rocking the returner bar on its support.

6. A returner bar and support therefor 95 for sugar cane mills including a main body portion, rounded extensions at each end thereof, supports having seats adapted to receive said rounded extensions, means for moving the support horizontally and vertically, and means for rocking the returner bar on its support. 100

7. A returner bar and support therefor for sugar cane mills including a main body portion having recesses in the lower edge of 105 each end, cylindrical members adapted to be held in said recesses and which provide a rounded bearing surface, bearing blocks, each having a seat adapted to receive said cylindrical members, supports adapted to provide a sliding support for the bearing blocks, means for adjusting the bearing blocks vertically and horizontally on the supports, and means for rocking the returner bar on its supports. 110

In testimony whereof I have signed my name to this specification in the presence of two subscribing witnesses.
